UNITED STATES PATENT OFFICE

WILLIAM H. STARING, OF WILLOUGHBY, OHIO, ASSIGNOR TO AUTOMATIC REGISTER-
ING MACHINE COMPANY, INC., A CORPORATION OF NEW YORK

CURTAIN-CLOSURE DEVICE

Application filed October 28, 1926. Serial No. 144,839.

This invention relates to an improvement in a curtain closure device, and more particularly to one for use in connection with enclosing the keyboard of a voting machine during part of the voting operations and substantially of the type set forth in the patent to Gillespie, 995,424, patented June 13, 1911.

In voting machines of the class specified the keyboard is covered during part of the voting operations by curtains, which are opened and closed by means of a lever which is in most cases operated by the voter. Moreover, until said keyboard is completely enclosed, the mechanism thereon cannot be actuated.

The primary object of this invention is to provide means which insure the complete enclosure of the keyboard, which means are herein set forth as acting to hold the curtain lever yieldably, but firmly, at the limit of its curtain closing movement.

Other objects of this invention reside in the details of construction set forth in the following specification and in the drawings which form a part thereof, and in which

Fig. 1 is a top plan view of a voting machine equipped with one embodiment of this invention, and showing in full lines the curtain lever in the open position, and in dotted lines the curtain lever in the closed position;

Fig. 2 is an enlarged side elevation of the latch embodying this invention shown in Figure 1; and

Fig. 3 is an enlarged plan view of said latch.

At the front of the voting machine designated in the drawing by the numeral 10 is provided a keyboard 11 which is enclosed by curtains 12 when the voter is indicating on the keyboard his preferences. This is shown in Figure 1 rather sketchily, and reference is directed to the Gillespie patent above mentioned and to the description and showing therein for a fuller exposition of these features.

Supported from the top of the machine 10 is a bowed rod 13, over which slide rings 14 to which the curtains 12 are suitably secured. The curtains 12 are opened and closed by the oscillation of a lever 15 pivotally supported on the machine 10 and adapted to be manually actuated by a handle 16.

An endless cord 17 passing over pulleys 18 is connected to the end of the lever 15 by a line 19. To the cord 17 are connected the ends 20 and 21 of the curtains 12, so as the cord 17 is moved the curtains are brought together to complete the enclosure of the keyboard 11, or are separated to expose the keyboard and permit the voter to approach or leave the keyboard.

A stop 22 limits the opening movement of the lever 15, while a latch 23 limits the closing movement thereof. The construction of the voting machine requires that the lever 15 be held at the closing limit during a part of the voting operation, and in order to insure that the latch 23 is employed in place of a simple limit stop such as is shown at 22.

The latch 23 comprises a plate 24 having at its base a flange 25, by which it is fixed to the machine 10 in any suitable manner, as by means of screws 26 passed through holes 27 in the flange 25. Pivotally mounted on the plate 24 as by a pin 28 is a catch 29. A spring 30 normally holds the catch 29 in contact with a finger 31 here shown as integral with the plate 24, and bent outwardly therefrom.

At the front of the plate 24 is a mouth 32, formed by jaws 33, 34, into which mouth the lever 15 enters as shown in Figure 2. At the outer end of the catch 29 is provided a lip 35, which normally extends above the upper edge of the jaw 34. Both the lip 35 and roller 36 project in the normal position of the latch into the path of the lever 15 as it enters the mouth 32. Since the catch is held in its normal position by the spring 30, the lever 15 as it enters the mouth 32 swings the catch on the pin 28 against the tension of the spring 30,

depressing the lip 35 and roller 36. When the lever 15 is fully within the mouth 32 the lip 35 and roller 36 are returned by the spring 30 to their normal positions, thus preventing 5 the lever from inadvertently leaving the mouth 32. A check 37 carried by the plate 24 and consisting of a rubber block 38 mounted in a pocket 39 functions to stop the closing travel of the lever 15.

10 The parts and elements just described are operated in the following manner. When the voter approaches the keyboard 11 the lever 15 is in the full line position shown in Figure 1. After passing between the ends 20 and 21 of the curtains 12 the voter, by means of the handle 16, swings the lever 15 into the dotted line position of Figure 1, thus bringing the ends 20 and 21 of the curtains together and completing the enclosure of the keyboard 11. 15 20 The lever 15 enters the mouth 32, being pushed by the voter past the lip 35 and roller 36. The lip 35 and roller 36 prevent the lever 15 from leaving the mouth 32 until the voter has finished and grasping the handle 16 25 swings the lever past the lip 35 and roller 36 across to the stop 22, thus separating the curtains 12.

While one embodiment of this invention has been shown and described, application is 30 not limited thereto, since it is obvious that other embodiments can be made without departing from the spirit and scope of this invention as set forth in the following claims.

Having thus set forth my invention what 35 I claim as new and for which I desire protection by Letters Patent is:

1. A curtain closure device comprising a lever by which said curtains are opened and closed, and a latch mounted to yieldably hold 40 said lever in closed position, said latch comprising a plate having jaws forming a mouth into which said lever enters, and a catch pivoted on said plate, which prevents said lever from inadvertently leaving said mouth.
- 45 2. A curtain closure device comprising a lever by which said curtains are opened and closed, and a latch mounted to yieldably hold said lever in closed position, said latch comprising a plate having jaws forming a mouth into which said lever enters, a catch pivoted on said plate, which prevents said lever from inadvertently leaving said mouth, and means for yieldably holding said catch in functioning position.
- 50 3. A curtain closure device comprising a lever by which said curtains are opened and closed, and a latch mounted to yieldably hold said lever in closed position, said latch comprising a plate having jaws forming a mouth into which said lever enters, a catch pivoted on said plate, which prevents said lever from inadvertently leaving said mouth, said catch including a lip which projects into said mouth and engages said lever.
- 55 4. A curtain closure device comprising a

lever by which said curtains are opened and closed, and a latch mounted to yieldably hold said lever in closed position, said latch comprising a plate having jaws forming a mouth into which said lever enters, a catch pivoted on said plate, which prevents said lever from inadvertently leaving said mouth, said catch including a lip and a roller mounted on said lip, both said lip and said roller projecting into said mouth and engaging said lever.

70 75 In testimony whereof I have affixed my signature.

WILLIAM H. STARING.
